IMMERSION TYPE THERMOSTAT

Vilynn O. Beam, Cleveland Heights, Ohio, assignor to The Bryant Heater Company, Cleveland, Ohio, a corporation of Ohio

Application October 8, 1937, Serial No. 168,003

2 Claims. (Cl. 200—137)

This invention relates to a thermostat of the immersion type adapted to control the temperature in a heating plant, such as a boiler or furnace, or like equipment.

5 The principal object of the invention is to provide a thermostat of this character which is simple in construction, efficient and reliable in operation, rugged, readily applied, and easily adjusted to vary the temperature at which the 10 device functions.

In the accompanying sheet of drawings wherein I have shown an embodiment which operates very effectively.

Fig. 1 is a vertical sectional view of the thermostat;

Fig. 2 is a front view; and

Fig. 3 is a fragmentary sectional view substantially along the irregular line 3—3 of Fig. 1.

The thermostat includes a metal housing 10 20 on the interior of which is supported an electric switch 11 which may be of any suitable construction, but generally consists of a switch blade which is adapted to be moved into or out of engagement with a fixed contact. At the bottom 25 of the housing is an opening 12 through which the conductors of the circuit controlled by the switch are extended into the housing and connected to the switch.

Screwed into an internally threaded boss 13 30 on the rear wall of the housing is a fitting 14 having a reduced externally threaded rear portion 15 by which the device is adapted to be fixed in the wall of the boiler or tank. This fitting additionally forms the main support for a thermal element of the tube and rod type which is adapted to extend into the water or steam of the boiler or tank and the temperature of which is to be controlled. This thermal element consists of a tube 16 of copper or other metal having a high coefficient of expansion and an inner rod 17 of a metal or alloy having practically a zero coefficient of expansion throughout the range of temperatures at which the instrument is adapted to function. In this instance the 40 rod 17 is fixed to the outer end of the tube 16, and this is preferably done by solidly screwing the rear end of rod 17 in a bushing 18 secured in the outer end of tube 16 and then sealing the outer end of the tube beyond the bushing with solder or other readily fusible metal or alloy 19. A cap 20 may be fitted onto the extreme outer end of the tube 16. To insure a leakproof joint between the tube and the fitting 14, after the tube is screwed into the rear end of the fitting 45

the joint may be sealed against leakage by solder indicated at 21.

The rod 17 extends beyond the tube and its forward end is threaded into a shaft 22 which extends horizontally across the housing, its rear end extending freely into the bore of the fitting 14 and its forward end being supported and journaled in a boss 23 in the front wall of the housing 10. The shaft 22 has a reduced end which extends forwardly beyond the front wall 10 of the housing and secured to its forward end is an adjusting knob 24 by which the shaft 22 may be turned on the threaded end of rod 17 to move the former forwardly or rearwardly and thereby adjust the instrument for different temperatures. 15 The knob 24 has a pointer cooperating with a scale 25 at the upper part of a plate 26 secured to the front wall of the housing.

As the temperature of the medium in which the element is immersed rises, the tube 16 pulls 20 the relatively inexpandable rod 17 rearwardly and with it moves the shaft 22. This movement is utilized to actuate the switch 11, and for that purpose I provide a switch operating member in the form of an angle lever or bell crank 27 25 which is connected by a flexible spring hinge 28 to the front wall of the housing of the switch 11 and has a substantially horizontal arm extending over the switch in position to actuate a switch operating pin 29 extending through the 30 top wall of the switch housing. Additionally, this bell crank has an arm 27b extending substantially vertically, this arm being notched at its upper end thus forming a yoke 27c which fits into a reduced portion 22a of the shaft 22. The 35 upstanding arm 27b is preferably slightly bowed and bears against a shoulder 22b at the forward end of the reduced part 22a.

The operation is as follows: The knob 24 will be set so that the instrument will function at 40 the desired high temperature. This, as before stated, can be varied by turning the knob 24 which adjusts the position of the shaft 22 and its shoulder 22b with reference to the upstanding arm of the bell crank 27. As the temperature 45 rises, the tube 16 expands lengthwise, pulling the relatively inexpandable rod 17 rearwardly with it. This moves the shaft 22 inwardly or rearwardly, there being sufficient clearance between the knob and the plate 25 to permit this 50 movement, and, after a predetermined movement, the switch operating bell crank 27 is rocked so as to sufficiently depress the pin 29 to actuate the switch. Generally this movement opens the switch, as when the switch is utilized 55

to control the supply of fuel to the furnace or boiler. Commonly, the switch operates the circuit of a solenoid which controls a main gas valve when the furnace or boiler is heated with gas, but it may control some other instrumentality when a different type of fuel is used.

Furthermore, by employing a reverse action switch, i. e., one which is closed by the rocking of the bell crank due to heating of the thermal element, the instrument may be employed, for example, to start a fan in a warm air system.

Obviously, when the temperature falls, the tube 16 contracts, moving forwardly the rod 17 and the shaft 22 and allowing the spring hinge 28 to restore the bell crank to its previous "off" position and to allow the switch to automatically return to its previous closed or open position, as the case may be.

While I have shown the preferred construction, I do not desire to be confined to the precise details shown but aim in my claims to cover all modifications which do not involve a departure from the spirit and scope of the invention.

Having thus described my invention, I claim:

25 1. In a thermostat of the character described, a housing, a thermal element projecting from the rear wall of the housing composed of an outer tubular member and an inner rod having different coefficients of expansion, the tubular member being secured to the housing and the rod being secured to the outer end of the tubular member and projecting therethrough into the housing, threads on the inner end of said rod,

a control element axially aligned with said rod and having a threaded socket to receive the threaded end of the rod and projecting at its forward end through the front wall of the housing, a switch in the housing offset from said rod and control element, an annular shoulder on said control element within the housing, an operating connection between said switch and control element arranged to bear upon said shoulder, and spring means for maintaining said operating connection in engagement with said shoulder.

10 2. In a thermostat of the character described, a housing, a thermal element projecting from the rear wall of the housing composed of an outer tubular member and an inner rod having 15 different coefficients of expansion, the tubular member being secured to the housing and the rod being secured to the outer end of the tubular member and projecting therethrough into the housing, threads on the inner end of said rod, a control element axially aligned with said rod and 20 having a threaded socket to receive the threaded end of the rod and projecting at its forward end through the front wall of the housing, a switch in the housing offset from said rod and control element, an annular shoulder on said 25 control element within the housing, and an angular operating lever pivotally mounted in the housing arranged to engage said shoulder in all rotary positions of the control element and arranged to engage and operate said switch.

VILYNN O. BEAM.
